ARTICLE OF REPOSE FOR SUPPORTING
THE BODY OF A PERSON

Anton Lorenz, Buffalo, N. Y.

Application September 29, 1949, Serial No. 118,599

18 Claims. (Cl. 155—105)

1

This invention relates to articles of furniture, and more particularly to reclining articles of furniture, wherein the seat and back-rest may be moved through the medium of a link-system from a sitting position into a reclined position and vice versa.

An object of the present invention is to provide a reclining article of furniture of above described type wherein during a displacement of the connected back-rest and seat from one position to another one the back-rest is moved through a greater angle than the seat, so that, if, for example, the back-rest and seat are moved from the sitting position into a reclined position the angle between said back-rest and said seat is increased.

Another object of the present invention is to provide a bed with a bed-bottom, the sections of which are adjustable relative to each other and may be readily brought from one position into another by a person resting on the bed.

A further object of the present invention is to improve on the art of reclining articles of furniture as now ordinarily made.

Other objects and structural details of the invention will be apparent from the following description when read in conjunction with the accompanying drawings forming part of this specification, wherein:

Fig. 1 is a side-elevational view of a reclining chair according to the invention, a portion of a side of the support being broken away.

Fig. 2 is a side-elevational view of a chaise longue according to the invention, a portion of a side of the supporting frame being broken away.

Fig. 3 is a side-elevational view of a different embodiment of a chaise longue according to the invention, a portion of a side of the supporting frame being broken away.

Fig. 4 is a top plane view of a bed according to the invention.

Fig. 5 is a side-elevational view of the bed shown in Fig. 4 some parts being shown in section, and

Fig. 6 is a side-elevational view of the bed similar to that shown in Fig. 5, wherein, however, the sections of the articulated bed-bottom are in an angular position relative to each other.

Referring now to Fig. 1, 20 generally indicates a support comprising side frames 22 and 24 rigidly connected with each other by cross-bars 26 and 28.

The lower end of back-supporting member or back-rest 30 is swingably mounted on a support

2

20 at 32. The rear end portion of a rockable seat 34 is swingably mounted on said support 20 at 36. The pivotal connection 36 between the seat 34 and the support 20 is spaced from the pivotal connection 32 between the back-rest 30 and the support 20.

An extension 38 rigidly connected with the seat 34 projects backwardly beyond the pivotal connection 36 between the seat 34 and the support 20 and beyond the pivotal connection 32 between the back-rest 30 and the support 20.

On each side of the chair a connecting link 40 is pivotally connected with the extension 38 of the seat 34 at 42 and with the back-rest 30 at 44.

15 An arm-rest 46 is rigid with said connecting link 40.

As will be readily understood, the portion of the back-rest 30 between the pivots 32 and 44, the connecting link 40 and the extension 38 of the seat 34 constitute the movable links of a four-sided link system, while the portion of the support 20 between the pivots 32 and 36 constitutes the stationary link of said four-sided link system.

The cross-bar 28 between the side frames 22

25 and 24 of the support 20 acts as a stop for limiting the sitting position of the seat 34 and the movable members of the chair connected therewith, as shown in full lines in Fig. 1. When the back-rest 30 is swung about its pivot 32 into the extreme reclined position, shown in dash and dot lines in Fig. 1, the seat 34 connected with said back-rest 30 in the manner described above is

30 swung about its pivot 36 into the reclined position shown in dash and dot lines. During such a displacement of the back-rest and seat from the sitting position into the reclined position the angle between the seat and the back-rest is increased. The extreme reclined position of the movable members of the chair, as shown in dash and dot lines, is limited by an abutment of the extension 38 against a stop 48 adjustably mounted in a slot 50 of the support 20. The stop 48 may be held in its adjusted position by means of a screw (not shown).

35 40 45 50 55 40 According to the embodiment shown in Fig. 2 again the back-rest 130 and seat 134 are pivoted to the supporting frame 120 of the chaise longue at remote points 132 and 136 respectively. The rearward extension 138 of the seat 134 is provided with a series of bores 152. A pin 142 pivotally connecting the lower end of the connecting link 140 of the seat 134 may be selectively engaged with a bore of the series of bores 152 of the extension 138 for an adjustment of the effective length of the latter.

According to the embodiment shown in Fig. 2 again the back-rest 130 and seat 134 are pivoted to the supporting frame 120 of the chaise longue at remote points 132 and 136 respectively. The rearward extension 138 of the seat 134 is provided with a series of bores 152. A pin 142 pivotally connecting the lower end of the connecting link 140 of the seat 134 may be selectively engaged with a bore of the series of bores 152 of the extension 138 for an adjustment of the effective length of the latter.

An arm-rest 146 is rigid with the connecting link 140 pivoted to the back-rest at 144.

A leg-supporting member or leg-rest 154 arranged at an angle to the seat 134 is rigid with the latter.

A cross-bar 156 connecting the side frames 122 and 124 of the support 120 with each other is arranged in a gap between the rear end portion of the seat 134 and the back-rest 130.

The sitting position of the movable members of the chaise longue, shown in full lines, is limited by a cross-bar 128 arranged for abutting engagement with the seat 134, the extreme reclined position of the movable members of the chair, shown in dash and dot lines, is limited by an abutment of the back-rest against a stop 148 carried by the support 120.

According to the embodiment of a chaise longue shown in Fig. 3 the back-rest 230 is pivoted to the support 220 at 232 and the rear end portion of the seat 234 is pivoted to said support 220 at 236, which is a point spaced from the pivotal connection 232 between the back-rest and the support. Again the rearward extension 238 of the seat 234 is provided with a series of bores 252. The pivot 242 connecting the lower end of the connecting link 248 with the extension 238 may be inserted into one or the other of said set of bores 252. The upper end of the connecting link 248 is pivotally connected with the back-rest 230 at 244.

Each arm-rest 246 is rigid with the back-rest 230 by screws 258.

The leg-rest 254 is swingably connected with the front end portion of the seat 234 at 260. The movements of the leg-rest 254 are controlled by a controlling mechanism which, in the embodiment shown in Fig. 3, is in the shape of a controlling link 262. One end of said controlling link 262 is pivoted to the leg-rest 254 at 264, the other end of said controlling link 262 is pivoted to the support 220 at 266.

The sitting position of the movable members of the chaise longue, shown in full lines, is limited by a cross-bar 228 of the support 220 arranged for abutting engagement with the seat 234. The extreme reclined position of the movable members of the chaise longue, shown in dash and dot lines, is limited by a stop 248 arranged on the support 220 for abutting engagement with the back-rest 230. During the movement of the connected back-rest 230 and seat 234 from the sitting position into the reclined position, the leg-rest 254 is brought into the dash and dot line position through the medium of the controlling link 262.

According to the embodiment shown in Figs. 4-6 the support 320 of the bed consists of the head-end 330, the foot-end 370 and the pair of longitudinal rails 372 rigidly connected with each other in any suitable manner.

The back-supporting member or head-section 330 of the bed bottom is swingably mounted at 332 on lugs 374 carried by the longitudinal rails 372 of the support 320. The end of the rockable seat-portion 334, adjacent to said head-section 330 is swingably mounted on said lugs 374 at 336 at a point spaced from the pivotal connection 332 between said head-section 330 and said lugs 374. The leg-supporting member or foot-section 354 of the articulated bed bottom is pivotally connected with the rockable seat-portion 334 at 360. On each side of the bed one end of the controlling link 362 is pivoted to a lug 376 of the foot-section 354 at 364, the other end of said control-

ling link 362 is pivoted at 366 to a lug 378 carried by a longitudinal rail 372 of the support 320.

On each side of the bed an extension 338 is rigid with the rockable seat-portion 334. Said extension projects beyond the pivotal connection 336 between the rockable seat-portion 334 and the support 320 and beyond the pivotal connection 332 between the head-section 330 and the support 320. Said extension 338 is provided with a series of recesses or notches 380.

On each side of the bed one end of a connecting link 340 is pivoted to the head-section 330 at 344. The other ends of said connecting links 340 are connected with each other by a transverse rod 382. Said transverse rod 382 may be selectively engaged with one or the other notch of the series of notches 380 of said extensions 338 for pivotal engagement. Therefore the connection between said transverse rod 382 and said notches 380 is disengageable so that the head-section 330, the seat-section 334 and the foot-section 354 may be brought into alignment with each other as shown in Figs. 4 and 5. Then the transverse rod 382 rests on a bracket 384 rigidly connected with the support 320, the lugs 336 of the head-section 330 are carried by the longitudinal rails 372, the seat-section 334 rests on the lugs 378 and the lugs 336 of the foot-section are carried by the longitudinal rails 372.

When the members of the bed are in the position shown in Figs. 4 and 5, a person may rest on a perfectly flat surface.

If a person wishes to rest on the bed in a reclined position with the legs elevated, for example, at first the head-section 330 is brought into the substantially vertical position 330', wherein the transverse rod 382 may be engaged with the first notch of the series of notches 380 of the extensions 338. During the movement of the head-section 330 from the horizontal position into said substantially vertical position the transverse rod 382 may slide along the bracket 384. After the engagement of the transverse rod 382 with said notches 380 of the extension 338 the head-section 330 may be swung from the position 330' shown in Fig. 5 into the reclined position shown in Fig. 6, whereby the rockable seat-portion 334 of the seat-section is brought from the horizontal position shown in Fig. 5 into the reclined position shown in Fig. 6 and the foot-section 354 is moved upwardly in planes parallel to each other from the position shown in Fig. 5 into the position shown in Fig. 6. Of course, during above described movement, the stationary portion 374 of the seat-section, rigid with the support 320, remains in its position.

If a different relative position between the head-section and the seat-section is desired in the reclined position, the transverse rod 382 of the connecting links 340 may be engaged with another notch of the series of notches 380, for example by moving the head-section 330 from the full-line position shown in Fig. 5 merely into the somewhat reclined position 330'' shown in said Fig. 5. On the other hand, of course, the head-section 330 may be used in said position 330'' as a support for the back of a person who wishes to sit up in the bed without having the legs in an elevated position.

It is understood that the aligned position of the sections 330, 334 and 354 of the bed bottom may be readily re-established by disengagement of the pivotal connections 330, 332 between the connecting links 340 and the extensions 338.

Although not shown in the drawings, it is un-

derstood, that every embodiment of a reclining article of furniture may be equipped with a locking device by means of which the movable members of the article may be held in any desired position.

I have described preferred embodiments of my invention, but it is understood, that this disclosure is for the purpose of illustration and that various omissions or changes in shape, proportion and arrangement of parts, as well as the substitution of equivalent elements for those herein shown and described, may be made without departing from the spirit and scope of the invention as set forth in the appended claims.

What I claim is:

1. An article of repose for supporting the body of a person comprising: a support, a seat-section, said seat-section including a rockable seat-portion pivoted at its rear end to said support, an extension rigid with said rockable seat-portion, said extension projecting backwardly beyond the pivotal connection between said rockable seat-portion and said support, a back-supporting member swingably mounted on said support at a point spaced from said pivotal connection between said rockable seat-portion and said support, and a connecting link pivoted at one of its end portions to said back-supporting member and at its other end portion to said extension of said rockable seat-portion.

2. An article of repose for supporting the body of a person comprising: a support, a seat-section, said seat-section including a rockable seat-portion pivoted at its rear end to said support, a back supporting member swingably mounted on said support at a point spaced from said pivotal connection between said rockable seat-portion and said support, an extension rigid with said rockable seat-portion, said extension projecting backwardly beyond the pivotal connection between said back-supporting member and said support, and a connecting link pivoted at one of its end portions to said back-supporting member and at its other end portion to said extension of said rockable seat-portion.

3. An article of repose for supporting the body of a person comprising: a support, a seat, the rear end portion of said seat being in pivotal connection with said support, an extension rigid with said seat, said extension projecting backwardly beyond the pivotal connection between said seat and said support, a back-rest swingably mounted on said support at a point spaced from said pivotal connection between said seat and said support, a connecting link pivoted at one of its end portions to said back-rest and at its other end portion to said extension of said seat, and an arm-rest rigidly connected with said connecting link.

4. An article of repose for supporting the body of a person comprising: a support, a seat, the rear end portion of said seat being in pivotal connection with said support, an extension rigid with said seat, said extension projecting backwardly beyond the pivotal connection between said seat and said support, a back-rest swingably mounted on said support at a point spaced from said pivotal connection between said seat and said support, a connecting link pivoted at one of its end portions to said back-rest and at its other end portion to said extension of said seat, and an arm-rest rigidly connected with said back-rest.

5. An article of repose for supporting the body of a person comprising: a support, a seat-sec-

tion, said seat-section including a rockable seat-portion pivoted at its rear end to said support, an extension rigid with said rockable seat-portion, said extension projecting backwardly beyond the pivotal connection between said rockable seat-portion and said support, a back-supporting member swingably mounted on said support at a point spaced from said pivotal connection between said rockable seat-portion and said support, a connecting link pivoted at one of its end portions to said back-supporting member and at its other end portion to said extension of said rockable seat-portion, and a leg supporting member connected with the front end of said rockable seat-portion.

6. An article of repose for supporting the body of a person comprising: a support, a seat, the rear end portion of said seat being in pivotal connection with said support, an extension rigid with said seat, said extension projecting backwardly beyond the pivotal connection between said seat and said support, a back-rest swingably mounted on said support at a point spaced from said pivotal connection between said seat and said support, a connecting link pivoted at one of its end portions to said back-rest and at its other end portion to said extension of said seat, and a leg-rest rigidly connected with the front end portion of said seat.

7. An article of repose for supporting the body of a person comprising: a support, a seat-section, said seat-section including a rockable seat-portion pivoted at its rear end to said support, an extension rigid with said rockable seat-portion, said extension projecting backwardly beyond the pivotal connection between said rockable seat-portion and said support, a back-supporting member swingably mounted on said support at a point spaced from said pivotal connection between said rockable seat-portion and said support, a connecting link pivoted at one of its end portions to said back-supporting member and at its other end portion to said extension of said rockable seat-portion, a leg supporting member pivotally connected with the front end portion of said rockable seat-portion, and a controlling mechanism operatively connected with a member of said article and said leg-supporting member for controlling the movements of the latter.

8. An article of repose for supporting the body of a person comprising: a support, a seat-section, said seat-section including a rockable seat-portion pivoted at its rear end to said support, an extension rigid with said rockable seat-portion, said extension projecting backwardly beyond the pivotal connection between said rockable seat-portion and said support, a back-supporting member swingably mounted on said support at a point spaced from said pivotal connection between said rockable seat-portion and said support, a connecting link pivoted at one of its end portions to said back-supporting member and at its other end portion to said extension of said rockable seat-portion, a leg supporting member pivotally connected with the front end portion of said rockable seat-portion, and a controlling link, one end of said controlling link being pivoted to said support, the other end of said controlling link being pivoted to said leg-supporting member.

9. An article of repose for supporting the body of a person comprising: a support, a seat-section, said seat-section including a rockable seat-portion pivoted at its rear end to said support,

an extension rigid with said rockable seat-portion, said extension projecting backwardly beyond the pivotal connection between said rockable seat-portion and said support, a back supporting member swingably mounted on said support at a point spaced from said pivotal connection between said rockable seat-portion and said support, a connecting link pivoted at one of its end portions to said back-supporting member and at its other end portion to said extension of said rockable seat-portion, and means whereby the effective length of said extension may be varied.

10. An article of repose for supporting the body of a person comprising: a support, a seat-section, said seat-section including a rockable seat-portion pivoted at its rear end to said support, an extension rigid with said rockable seat-portion, said extension projecting backwardly beyond the pivotal connection between said rockable seat-portion and said support, a back-supporting member swingably mounted on said support at a point spaced from said pivotal connection between said rockable seat-portion and said support, and a connecting link pivoted at one of its end portions to said back-supporting member and at its other end portion to said extension of said rockable seat-portion, the pivotal connection between said connecting link and said extension being disengageable.

11. An article of repose for supporting the body of a person comprising: a support, a seat-section, said seat-section including a rockable seat-portion pivoted at its rear end to said support, an extension rigid with said rockable seat-portion, said extension projecting backwardly beyond the pivotal connection between said rockable seat-portion and said support, a back-supporting member swingably mounted on said support at a point spaced from said pivotal connection between said rockable seat-portion and said support, a connecting link pivoted at one of its end portions to said back-supporting member and at its other end portion to said extension of said rockable seat-portion, and limiting means arranged on said support for abutting cooperation with said extension so as to limit an extreme position thereof.

12. An article of repose for supporting the body of a person comprising: a support, a seat-section, said seat-section including a rockable seat-portion pivoted at its rear end to said support, an extension rigid with said rockable seat-portion, said extension projecting backwardly beyond the pivotal connection between said rockable seat-portion and said support, a back-supporting member swingably mounted on said support at a point spaced from said pivotal connection between said rockable seat-portion and said support, a connecting link pivoted at one of its end portions to said back-supporting member and at its other end portion to said extension of said rockable seat-portion, and a stop adjustably arranged on said support for abutting cooperation with said extension so as to limit an extreme position thereof.

13. An article of repose for supporting the body of a person comprising: a support, a seat, the rear end portion of said seat being in pivotal connection with said support, an extension rigid with said seat, said extension projecting backwardly beyond the pivotal connection between said seat and said support, a back-rest swingably mounted on said support at a point spaced from said pivotal connection between said seat

5

and said support, a connecting link pivoted at one of its end portions to said back-rest and at its other end portion to said extension of said seat, a leg-rest rigidly connected with the front end portion of said seat, and an arm-rest rigidly connected with said connecting link.

14. An article of repose for supporting the body of a person comprising: a support, a seat, the rear end portion of said seat being in pivotal connection with said support, an extension rigid with said seat, said extension projecting backwardly beyond the pivotal connection between said seat and said support, a back-rest swingably mounted on said support at a point spaced from said pivotal connection between said seat and said support, a connecting link pivoted at one of its end portions to said back-rest and at its other end portion to said extension of said seat, a leg-rest pivotally connected with the front end portion of said seat, a controlling link, one end of said controlling link being pivoted to said support, the other end of said controlling link being pivoted to said leg-rest, and an arm-rest rigidly connected with said back-rest.

15. An article of repose for supporting the body of a person, comprising: a support including longitudinal rails, a back-supporting member pivoted to said support, a seat-section including a stationary seat-portion and a rockable seat-portion, said stationary seat-portion being rigid with said support, said rockable seat-portion being pivoted to said support at a point spaced from the pivotal connection between the back-supporting member and the support, a leg-supporting member, said leg-supporting member being connected with said rockable seat-portion, an extension rigid with said rockable seat-portion, said extension projecting beyond the pivotal connection between said rockable seat-portion and said support, and a connecting link, one end of said connecting link being in pivotal connection with said back-supporting member, the other end of said connecting link being in pivotal connection with said extension, and the pivotal connection between said connecting link and said extension being disengageable whereby said back-supporting member, said seat-section and said leg-supporting member may be brought substantially in alignment with each other so as to form a bed-bottom resting on said longitudinal rails.

16. An article of repose for supporting the body of a person, comprising: a support including longitudinal rails, a back-supporting member pivoted to said support, a seat-section including a stationary seat-portion and a rockable seat-portion, said stationary seat-portion being rigid with said support, said rockable seat-portion being pivoted to said support at a point spaced from the pivotal connection between the back-supporting member and the support, a leg-supporting member, said leg-supporting member being connected with said rockable seat-portion, an extension rigid with said rockable seat-portion, said extension projecting beyond the pivotal connection between said rockable seat-portion and said support, a connecting link, one end of said connecting link being in pivotal connection with said back-supporting member, the other end of said connecting link being in pivotal connection with said extension, the pivotal connection between said connecting link and said extension being disengageable whereby said back-supporting member, said seat-section and said leg-supporting member may be brought substantially in alignment with each

other so as to form a bed-bottom resting on said longitudinal rails, and means for selectively engaging said connecting link with different points of said extension.

17. An article of repose for supporting the body of a person, comprising: a support including longitudinal rails, a back-supporting member pivoted to said support, a seat-section including a stationary seat-portion and a rockable seat-portion, said stationary seat-portion being rigid with said support, said rockable seat-portion being pivoted to said support at a point spaced from the pivotal connection between the back-supporting member and the support, a leg-supporting member, said leg-supporting member being swingably connected with said rockable seat-portion, an extension rigid with said rockable seat-portion, said extension projecting beyond the pivotal connection between said rockable seat-portion and said support, a connecting link, one end of said connecting link being in pivotal connection with said back-supporting member, the other end of said connecting link being in pivotal connection with said extension, the pivotal connection between said connecting link and said extension being disengageable whereby said back-supporting member, said seat-section and said leg-supporting member may be brought substantially in alignment with each other so as to form a bed-bottom resting on said longitudinal rails, and a controlling link, one end of said controlling link being pivoted to said support, the other end of said controlling link being pivoted to said leg-supporting member.

18. An article of repose for supporting the body of a person, comprising: a support including longitudinal rails, a back-supporting member pivoted to said support, a seat-section including a stationary seat-portion and a rockable seat-portion,

5 said stationary seat-portion being rigid with said support, said rockable seat-portion being pivoted to said support at a point spaced from the pivotal connection between the back-supporting member and the support, a leg-supporting member, said leg-supporting member being swingably connected with said rockable seat-portion, an extension rigid with said rockable seat-portion, said extension projecting beyond the pivotal connection between said rockable seat-portion and said support, a connecting link, one end of said connecting link being in pivotal connection with said back-supporting member, the other end of said connecting link being in pivotal connection with said extension, the pivotal connection between said connecting link and said extension being disengageable whereby said back-supporting member, said seat-section and said leg-supporting member may be brought substantially in alignment with each other so as to form a bed-bottom resting on said longitudinal rails, means for selectively engaging said connecting link with different points of said extension, and a controlling link, one end of said controlling link being pivoted to said support, the other end of said controlling link being pivoted to said leg-supporting member.

ANTON LORENZ.
